UNITED STATES PATENT OFFICE.

SAMUEL J. DUNKLEY, OF KALAMAZOO, MICHIGAN, ASSIGNOR TO DUNKLEY COMPANY, OF KALAMAZOO, MICHIGAN, A CORPORATION OF MICHIGAN.

PARING AND PITTING KNIFE.

1,374,289.

Specification of Letters Patent. Patented Apr. 12, 1921.

Application filed January 28, 1919. Serial No. 273,591.

To all whom it may concern:

Be it known that I, SAMUEL J. DUNKLEY, a citizen of the United States, residing at Kalamazoo, Michigan, have invented certain 5 new and useful Improvements in Paring and Pitting Knives, of which the following is a specification.

This invention relates to an improved paring and pitting knife. The object of the 10 invention is to provide an improved oscillatory cutting knife for the pitting and paring of fruit.

Objects of the invention pertaining to details and economies of construction and 15 operation will definitely appear from the detailed description to follow.

I accomplish the objects of my invention by the devices and means described in the following specification. The invention is 20 clearly defined and pointed out in the claim.

A structure which is a preferred embodiment of my invention is fully illustrated in the accompanying drawing, forming a part of this specification, in which:

25 Figure I is a longitudinal detail sectional view through a paring and pitting knife structure embodying the details of my invention, some of the parts being shown in full lines.

30 Fig. II is a detail transverse sectional view on the line 2—2 of Fig. I.

Fig. III is a detail transverse sectional view on line 3—3 of Fig. I.

Fig. IV is a detail view of a straight-edged knife with a guard.

Fig. V is a transverse detail sectional view of the knife, taken on line 5—5 of Fig. IV.

40 Fig. VI is an enlarged detail view of a portion of the blade 11 showing its serrations.

In the drawing similar numbers of reference refer to similar parts throughout the several views, and the sectional views are taken looking in the direction of the little 45 arrows at the ends of the section lines.

Considering the numbered parts of the drawing, 1 is the handle for the tool. Axially disposed in the end of this handle is a slide 2 having a stem 3 which extends 50 through the bracket 4 into a bearing 5 at the opposite end. This slide is provided with collars 6, 6 on its stem and is caused to

reciprocate by rotation of the shaft 7, which is provided with a disk 8 at its end provided with a wrist pin 9 which extends into and 55 engages between the collars 6, 6. When the shaft 7 is revolved, the action of the pin 9 between the collars 6, 6 causes the reciprocation. The shaft 7 is provided with suitable connection 10 to a flexible shaft or 60 other suitable driving means.

On the reciprocating slide 2 is supported the curved knife 11 which is provided with a straight shank 12 and is retained in a socket in the end of the slide 2 by set screw 65 13. The edge of this knife is serrated.

The shaft 7 is caused to revolve, preferably, at the rate of about 1800 revolutions per minute, so that the knife 11 vibrates very rapidly. It is found that this is a very 70 effective device for removing pits and cores from fruit and for any purpose of that kind.

By substituting the straight knife 14 with a guard 15, the knife is very effective for the peeling of pears or of any hard fruit, as 75 green peaches and the like, or for any use where a straight knife is needed. The reciprocation greatly enhances the cutting quality. The knife has the effect of seeming to be very sharp.

80 I have thus described the preferred means for inducing the reciprocation, but it is very clear that various means might be provided for the purpose and I wish to claim my invention broadly as well as specifically, as 85 indicated in the appended claims.

Having thus described my invention, what I claim as new and desire to secure by Letters Patent is:

90 In a paring and pitting knife, the combination of a handle, a slide axially disposed within the handle and a means to reciprocate the slide, and a curved knife axially disposed to said handle and carried by said slide and adapted to be reciprocated thereby, 95 as specified.

In witness whereof, I have hereunto set my hand and seal in the presence of two witnesses.

SAMUEL J. DUNKLEY. [L.S.]
